CARD RECORD APPARATUS

John W. Whitson, New York, N. Y., assignor of
one-half to Clare H. Whitson, New York, N. Y.

Application January 18, 1944, Serial No. 518,694

19 Claims. (Cl. 129—16.1)

1

This invention relates to improvements in the card record apparatus shown in the United States Patents 2,002,807 and 2,002,808, issued to me May 28, 1935 and Patent 1,846,779, issued to me on Feb. 23, 1932 and my pending application for patent for card record apparatus filed Feb. 22, 1943, Serial Number 476,725, now Patent No. 2,379,943.

One of the objects of the invention is to provide means, automatic in operation, for subjecting the cards to the influence of intermittent magnetic attraction so as to more readily move the selected cards.

Another object of the invention is to provide means, automatic in operation, for aligning the cards in relation to the selecting elements of the apparatus.

Another object of the invention is to provide electrically operable means for restoring the selecting elements to their normal position.

With the above mentioned and other objects in view, the invention comprises in the novel construction and combination of parts hereinafter described, illustrated in the accompanying drawings, and set forth in the claims hereto appended, it being understood that various changes in the form, proportion, size and details of construction within the scope of the claims may be resorted to without departing from the spirit or sacrificing any of the advantages of the invention.

In the accompanying two sheets of drawings: Fig. 1 is a longitudinal cross-section taken on the line 1—1 of Figs. 4 and 5.

Fig. 2 is a right side elevation with the outside casing partly removed.

Fig. 3 is a lateral cross-section taken on line 3—3 of Fig. 1.

Fig. 4 is a partial plan view.

Fig. 5 is a partial plan view showing a different method of electrical control than that shown in Fig. 4.

Fig. 6 is a wiring diagram for the electrical controls shown in Fig. 4.

Fig. 7 is a wiring diagram for the electrical controls shown in Fig. 5.

Fig. 8 is a modification of the wiring diagrams shown in Figs. 6 and 7.

Fig. 9 is a partial view of a modified form of bolt 122 in relation to armature plate 42.

Fig. 10 is a partial view of the modified form of bolt 122 in relation to armature plate 42 and electro-magnet 38.

In detail the construction illustrated in the drawings comprises a casing 1, made up of a card compartment 2, and a mechanism compart-

2

ment 3 and a keyboard 4. Cards 5 are provided with recesses 6 on the bottom edges thereof and adjacent to each of the opposite sides thereof to be received on the carrier bars 7 of a card carrier. The carrier bars 7 of the tray or card carrier are adapted to engage the recesses 6 when removing the cards from the card compartment or installing the cards therein. The card supporting bars 7 are provided with a plurality of card spacing elements 8 adjustable throughout the length thereof whereby a number of cards are confined between each pair of spacers. The bars 7 and the elements 8 form part of the card carrier. A plurality of holders 9 are arranged laterally across the casing 1 between the front and rear ends thereof, the upper edges of said holders lying in a common plane slightly below the line of the bottom surface of card compartment 2.

10 The casing 1 is provided with supporting frames 35 each of which has a shoulder on its top edge at respectively opposite sides thereof which form the bottom supporting surfaces of the said compartment 2. When the cards are in the compartment the bottom edges thereof at the opposite corners rest on the upper face of shoulders 10 and the carrier bars 7 of the tray drop below the plane of said shoulders 10 into recesses provided in the bottom of the card compartment on the opposite sides thereof between the shoulders 10. The holders 9 are provided with crosswise recesses 11 therein adjacent to each of the opposite ends thereof and disposed next to the opposite sides of the casing into which

15 30 35 40 45

the longitudinally extended bars 7 of the card carrier are adapted to rest when said card carrier is placed within the card compartment 2. The card carrier supports all of the cards that are confined within the card compartment and said carrier may be removed at will to permit various groups of cards supported in similar carriers to be removed to and from the compartment at will.

The holders 9 are provided with a series of elongated slots 12 cut down from an edge thereof and extending across the length of said cross members. The corresponding slots 12 of all of the holders 9 are in alignment with each other. The lower edge of each of the holders 9 is turned into a U section so that the edge 14 is bent upwardly to lie on a plane substantially flush with the bottom of slots 12.

A selector bar is confined in each of the slots 12 in each of the holders 9, each of said selector

bars extending from a point rearward of the rearmost holder 9 to a point forward of the foremost holder 8. The upper edge of each of the selector bars 15 lies substantially flush with the upper edges of the holders 9. Each of the bars 15 has inclined slots 16 formed therein through which rods 17 extend, said rods being attached at their opposite ends to the opposite sides of the inside supporting frames 35.

A plurality of finger keys 18 comprising the keyboard 4 are mounted on levers 19 which in turn are rotatively journaled on a cross bar 20. Each of the key levers 19 engages one of the selector bars 15 beyond the fulcrum bar 20. Thus when any one of the key fingers 18 is depressed the opposite end of the key lever is moved upwardly causing a corresponding upward and forward movement of the related selector bar 15 within the limits of movement prescribed by the inclined slots 16 and the cross rods 17. Each lever 19 on the opposite sides of the pivotal axis 20 is confined in the respective guide members 21 and 22 which are substantially the same as holders 9 in the inverted position, to eliminate lateral play of said levers during movement thereof.

The forward end of each selector bar 15 is provided with an arm 23 thereon to which one end of a cutter 24 is vertically and slidably and detachably secured. Each cutter member 24 consists of an inverted U-shaped element having one end attached to the selector bar as described and the opposite end of said cutter provided with an opening 25 through the face thereof, one edge 26 of said opening being cut at an angle to provide a shearing or cutting edge. The cutters 24 lie alongside of each other across the width of casing 1. The bottom face of each of the cutters rests on a spring finger 27, while the upper face of the cutters is confined below the bottom side of shear bar 29. The spring fingers 27 engage the interior of their respective cutters 24 and tend to force the upper side of said cutters upwardly against the bottom side of shear bar 29. The described method of mounting the cutters permits of a slack or "loose play" fit of said parts and the spring fingers 27 serve to hold each of the cutters in proper operating position. The spring tension of the finger on the cutters also supplies the necessary friction to maintain each selector bar in its elevated position. When the cutters are inoperative the outer ends thereof lie flush with the outer face of the shear bar 29. When any one of the finger keys is depressed, in addition to raising a corresponding selector bar 15, the movement of the selector bar causes the cutter attached thereto to be projected forwardly of the shear bar 29 into the cutting position, as shown in Figs. 1 and 4.

The cards 5 are provided with a plurality of spaced lugs or abutments 30 along the bottom edge thereof, the spaces between the plurality of lugs corresponding to the number of selector bars 15. Each of the lugs or the space between any pair of lugs may represent or be designated by any letters of the alphabet, or by numbers, or by any other emblems or indicia to suit the particular conditions of the work of the card. The lugs or spaces on the bottom of the card are related to the finger keys on the machine whereby each key on the keyboard when depressed will always move its selector bar into the space on the bottom of the card corresponding with that key. The card 5 as shown in Fig. 3 has magnetically attractive strips 31 fastened at the opposite verti-

cal edges. The cards must be responsive to magnetic attraction.

To this point the specification has followed that of Patent 2,002,808 and my pending application for patent for card record apparatus filed February 22, 1943, Serial Number 476,725, now Patent 2,379,943 dated July 10, 1945, as to parts numbers and description because the parts are similar.

In order to prepare the card 5 shown in Fig. 3 so that it may be selected from a group of cards confined in the card compartment, the operator first depresses switch 120 to operate solenoid 121 and cause bolt 122 to be moved inward (to the left) releasing plate 42 for movement. Holding switch 120 depressed, the operator then depresses the first of certain keys on the keyboard corresponding to the name or title or other key data which will distinguish that particular card from the other cards. The pressing of the first key will move armature plate 42 to its upmost position, releasing the balance of the keys for movement as desired. After the depression of the first key the operator releases switch 120. The keys thus depressed will cause corresponding cutter members to be projected beyond the face of shear bar 29 into position shown in Fig. 4. With the cutters in this position the card would have the lugs 30 on the bottom edge thereof dropped down into the openings 25 of the cutters. The operator 30 would then press switch 32.

Switch 32 has main power lead 33 connected to one of its contacts and wire 34 connects it to one end of the coil of electro-magnet 38, the other end of coil 38 is connected to main power lead 43 by wire 39. Electro-magnet 38 is mounted in the mechanism compartment 3 and is fastened at each end to the side frames 35 as at 41. Plate 42 is fastened on rod 43 as at 44. Rod 43 extends between side frames 35 and is journaled therein 40 as at 45, one end of plate 42 contacts a notch in each of the selector bars 15 as at 46 so that upon the raising of any of the selector bars plate 42 will move with the selector bar and be raised from the face of electro-magnet 38, to a position 45 as indicated in dotted lines. When electro-magnet 38 is energized by the closing of switch 32, solenoid 121 is also energized and bolt 122 is moved to the left so that plate 42 will be unobstructed in its movement toward electro-magnet 38, armature plate 42 will be attracted by and moved toward electro-magnet 38 thus moving with it any of the raised selector bars to their downmost position, this action will cause all of the cutters to be returned simultaneously to the concealed position which action of the cutters causes the lugs on the bottom edge of the cards to be cut therefrom.

When plate 42 is in its downmost position, bolt 122 is in the position shown in Fig. 3, locking plate 42 against electro-magnet 38 preventing any movement of plate 42, which in turn prevents any movement of the keys 18 of the keyboard 4.

Solenoid 121 has a casing 123 with a flange piece 124 which is fastened to frame 35, a coil 125 and a spring 127 which keeps bolt 122 in its extended position, locking plate 42 against magnet 38. Bolt 122 extends through a hole in frame 35 and has a shoulder which bears against frame 35 which restrains its outward movement. When solenoid 121 is energized, bolt 122, which is the core of the solenoid will be drawn into the solenoid unlocking plate 42 so that it can move when 75 any of the keys 18 of the keyboard 4 are de-

pressed and the selector bar associated with a depressed key is raised to its upmost position.

Connected to switch 120 is lead 52 of electro-magnet 53. When solenoid 121 is energized, electro-magnet 53 is also energized and draws the cards 5 in the card compartment to it aligning them so that their lugs 30 register with the selector bars 15. Switch 120 is connected to main power lead 33, and to magnet 53 by wire 52, magnet 53 is connected to main power lead 40 by wire 70, wire 128 connects one end of coil 126, of solenoid 121, to wire 52 the other end of coil 126 is connected to main power lead 40 by wire 129. Thus it can be seen that before the operator can operate the keyboard, the keyboard must be released by operating switch 120 and that the operation of switch 120 will also energize electro-magnet 53 and this will align the lugs of the cards in register with the selector bars 15. Patent 2,002,808 does not provide for this but depends on the operator seeing that the cards are manually aligned before operating the keyboard, as stated on page 2, column 2, lines 53 to 55 inclusive. Patent 2,002,807 while showing means for aligning the cards, the means is not operable in association with a means for locking the selector bars and the keyboard so as to automatically provide that the aligning function be performed before the keyboard is operated.

Connected into the circuit of switch 32 is wire 130 connecting to wire 52 of electro-magnet 53 so that when magnet 38 is energized magnet 53 will also be energized and attract the cards in the card compartment to it and align them with the selector bars 15.

The card from which certain of the lugs have been cut or removed would then be placed in the card carrier in the card compartment 2 as shown in Fig. 3. The operator would then depress switch 120 and would then depress the first of the series of keys corresponding to the cut out portions left on the cards as a result of the removal of the lugs, switch 120 would then be released and the balance of the series of keys would be depressed. The keys when depressed will move their selector bars upwardly into the cut out spaces between the lugs on said card. The selector bars would also assume a position in the spaces between the lugs on all the other cards, in the card compartment, which either have or do not have cut out portions thereon. Obviously cards that do not have lugs cut from the bottom edge thereof could not have any lateral movement inasmuch as the width of the selector bar fits the space between any pair of lugs. However, on those cards where one or more lugs have been removed to provide a space between lugs greater than the width or thickness of the selector bars then such cards can move laterally relative to the selector bars extended between the lug spaces thereon. After the desired number of keys have been depressed and the selector bars engaged with the aforesaid selector spaces on the bottom of the cards the operator would depress switch 54, shown in Figs. 4 and 6.

Connected to switch 54 is main power lead 33. An electric motor 59 is mounted in mechanism compartment 3. In the casing of the motor 59 is commutator 60 having a contact segment 61, 70 both shown in dotted lines as in Fig. 2 also mounted in the motor are brushes 62, 63 and 64, these brushes bear against the commutator and make and break contact with contact segment 61 as it is revolved under them by the

motor. Commutator 60 may be gear driven from the motor at any desired speed. Motor 59 has terminals 65 and 66 for connecting it to its source of power. Terminal 66 is connected to main power lead 40 and terminal 65 is connected by wire 68 to switch 54. Wire 68 is also connected to brush 63 and coil 131, of magnet 72. The other end of coil 131 is connected to main power lead 40 by wire 132. Brush 64 is connected by wire 69 to one end of the coil of electro-magnet 53 the other end of the coil being connected by wire 70 to power lead 40. Brush 62 is connected by wire 71 to one end of coil 133 of electro-magnet 72, the other end of the coil being connected by wire 134 to power lead 40.

When switch 54 is pressed, closing its circuit, motor 59 will start operating, revolving commutator 60 under brushes 62, 63 and 64, as contact segment 61 passes under the brushes, electro-magnet 53 and coil 133 of electro-magnet 72 will be alternately energized. When the contact segment 61 is in contact with brushes 62 and 63, coil 133 of electro-magnet 72 will be energized, when the contact segment is in contact with brushes 63 and 64 electro-magnet 53 will be energized. Coils 131 and 133 of electro-magnet 72 are together of greater power than electro-magnet 53. On one end of the shaft of commutator 60 is a crank disc 135 having a connecting rod 136 connected to lever 137. Lever 137 bears against the underside of electro-magnet 72 and the rotation of crank disc 135 causes an oscillating movement of lever 137 which together with the tension of spring 138 causes the face of electro-magnet 72, adjacent the cards 5, to swing in an arc from a position as shown in full lines (Fig. 3) to the position shown in dotted lines. When the face of electro-magnet 72 is in the position shown in dotted lines, it can exert greater magnetic force on the cards than when it is inclined to the cards. Patents 1,846,779, 2,002,807 and 2,002,808 and my pending application for patent for card record apparatus filed Feb. 22, 1943, Serial Number 476,725 do not show a means automatic in operation for moving and energizing their card moving magnets. Electro-magnet 72 is mounted on hinges 139 each of which has a leaf 140 fastened to frame 35 and a leaf 141 fastened to electro-magnet 72. Leaf 141 has a forked end 142 fitting either side of stud 77 and limiting leaf 141 and electro-magnet 72 in its movement are lock nuts 143 and 144. At the time when coil 133 is energized lever 137 has moved electro-magnet 72 to the position indicated in dotted lines and forked end 142 of leaf 141 bears against lock nut 143, when coil 133 is de-energized lever 137 moves to the position shown in dotted lines and spring 138 moves electro-magnet 72 so that forked end 142 of leaf 141 stops against lock nut 144. Any card or cards that have been attracted and moved to electro-magnet 72 will be held to the electro-magnet and move with it, as indicated in dotted lines, because the cards will be held against electro-magnet 72 by the attraction of coil 131 which remains energized as long as switch 54 is pressed. Operation of switch 54 will cause electro-magnets 53 and 72 to alternately attract the cards, en masse, toward them. Magnet 72 being of greater power will move the card or cards not held by the raised selector bars, first, to the horizontal position shown in dotted lines in Fig. 3, and away from the influence of electro-magnet 53, and then to the second or inclined position shown in dotted lines. Switch 54 is then released stopping motor 59 and de-energizing the circuits of electro-mag-

nets 53 and 72. It has been determined that when commutator 60 operates at approximately 120 R. P. M., the operator can release switch 54 so that the position of lever 137 in relation to the magnet 72 is substantially that shown in dotted lines in Fig. 2 and the position of the card an inclined position as indicated in dotted lines in Fig. 3, a mechanical means could also be employed to arrest the lever 137 and the magnet 72 at these positions. The card may then be removed from the apparatus by the operator. Switch 32 would then be pressed causing magnet 38 to become energized, attracting armature plate 42 to the magnet and moving the raised selector bars 15 to their downmost position, thus preparing the device for another card selection. When switches 32, 54, and 120 are depressed to their closed positions they remain in this position only as long as pressure is maintained on them, when pressure is released they return to their normal or open positions.

When either of the electro-magnets 53 or 72 is energized the magnetic fields created will cause the magnetic strips 31, on the cards, to become polarized alike causing the cards to be repelled from each other, this and the en masse intermittent attraction of the cards causing an agitating of the mass of cards tending to loosen them from frictional contact with each other. Electro-magnets 53 and 72 may be energized with either direct or alternating current. When energized with alternating current the effect of direct current may be simulated by regulating the speed of commutator 60 so as to control the length of time segment 61 is in contact with brushes 62, 63 and 64 and thus determine the number of cycles of alternating current that will pass into the magnet circuits. The patents previously issued to me do not show means for energizing their magnets at predetermined intervals. It is optional to use electro-magnet 53 in conjunction with electro-magnet 72. If wire 69 is not connected to brush 64 then only magnet 72 would be intermittently energized. If only the card moving magnet is used, as in Patent 2,002,808, then magnet 53 and its connections would not be included and only magnet 72 would be intermittently energized.

When the cards are in the card compartment in position to be attracted to the electro-magnets the opposite edges of the cards are supported on the shoulders 10 in the bottom of the card compartment and hence are free to move laterally with a minimum of resistance. Electro-magnet 53 rests on one of the shoulders 10 and is adjustably fastened thereto by cap screws 14, studs 15 adjustably hold electro-magnet 53 to the bottom of mechanism compartment 3.

When switch 32 is operated to return the raised selector bars 15 to position in readiness for repeating the selecting operation, such return movement of the selector bars causes the keys 18 to be raised to their operating position.

Figs. 5 and 7 show an alternate method for controlling the circuits of electro-magnets 53 and 72. Switches 32 and 120 control electro-magnets 53 and 38, and solenoid 121 as already described. Switch 54 and motor 59 are replaced by switches 145 and 146. Switch 145 is connected by wire 147 to coil 131 of electro-magnet 72 and to switch 146 by wire 148 and to main power lead 33. Switch 146 is connected to main power lead 33 and by wire 149 to coil 133 of electro-magnet 72 and by wire 150 to electro-magnet 53.

Operation as follows: Switch 120 and the 75 net 38, bears against the beveled face of bolt 122,

keys 18 of the keyboard 4 are operated as hereinbefore described. Switch 145 is then pressed and held so, this energizes electro-magnet 53 and coil 131 of electro-magnet 72. Switch 146 is then pressed this de-energizes electro-magnet 53 and energizes coil 133 of electro-magnet 72. The magnetic attraction between the cards in the card compartment and electro-magnet 72, when energized by coils 131 and 133, causes magnet 72 to move to the vertical position shown in dotted lines in Fig. 3, and attract to the magnet any card or cards not held by the selector bars, and away from the influence of electro-magnet 53. Switch 146 is then released de-energizing coil 133 of electro-magnet 72 and energizing electro-magnet 53, electro-magnet 72 will move to its inclined position due to the tension of spring 138 and the attracted card or cards will move with electro-magnet 72 due to the magnetic attraction of coil 131. Switch 145 is then released de-energizing electro-magnet 53 and coil 131 of electro-magnet 72. The operator would then remove the selected card. Switch 32 would then be pressed to restore the machine to its initial position for selecting a card. Gravity could be used to move magnet 72 to its inclined position instead of spring 138, in either event the combined attraction of coils 131 and 133 and the cards in the card compartment overcomes the tension of spring 138, or gravity, and permits magnet 72 to move to its vertical position.

The residual magnetism of the core of electro-magnet 72, or a permanent magnet core may be used for moving the selected cards to their inclined position. In this case coil 131 would be omitted and only coil 133 of magnet 72 would be used. This would also be the case when magnet 72 remains in fixed inclined position as in Patent 2,002,808 and in my pending application for patent for card record apparatus Serial Number 476,725, filed February 22, 1943. Then lock nut 143 would be moved against fork 142, of hinge leaf 141, and crank disc 135, crank 136, lever 137 and spring 138 would be omitted.

With magnet 72 in fixed inclined position the apparatus would operate as follows: Switch 120 and the keys 18 of the keyboard 4 are operated as hereinbefore described. Switch 54 is then pressed, motor 59 will start operating, revolving commutator 60 under brushes 62, 63 and 64, as contact segment 61 passes under the brushes, electro-magnets 53 and 72 will be alternately energized. When the contact segment 61 is in contact with brushes 62 and 63 electro-magnet 72 will be energized, when the contact segment is in contact with brushes 63 and 64 electro-magnet 53 will be energized. Electro-magnet 72 is of greater power than electro-magnet 53. Operation of switch 54 will cause electro-magnets 53 and 72 to alternately attract the cards, en masse, toward them. Magnet 72 being of greater power will move the card or cards not held by the raised selector bars, to the inclined position shown in dotted lines in Fig. 3, and away from the influence of magnet 53. The card may then be removed from the apparatus by the operator. Switch 32 would then be pressed to restore the apparatus to its initial position for selecting a card. Switches 32, 54, 120, 145 and 146 are all of the push button type and are held depressed by finger pressure, when pressure is removed they return to their normal positions.

Figs. 9 and 10, show a modified form of the bolt 122. In this case the bolt has a beveled face and plate 42, in returning to its position against magnet 72, bears against the beveled face of bolt 122,

thus moving the bolt to the left, allowing for the unobstructed movement of plate 42 toward magnet 38. Fig. 8 shows the changes in the wiring diagrams shown in Figs. 6 and 7 when the modified bolt form is used, as shown in Figs. 9 and 10. Wire 128 is connected to switch 120, instead of being connected to wire 52.

Patent 2,002,808 while showing a means for adjusting the card moving magnet, closer to and away from the cards in the card compartment, the means is not operable in association with the energizing of the card moving magnet, as is the case in the present invention.

Having now described and illustrated one form of my invention, I wish it to be understood that my invention is not to be limited to the specific form or arrangement of parts herein described and shown, except as set forth in the appended claims.

Having thus described this invention, what I claim and desire to secure by Letters Patent is:

1. In a card record apparatus in which magnetically attractive cards having lugs formed in an edge thereof are selectively locked against movement by engaging the lugs on the cards with selectively settable selector members common to all of the cards and a card moving magnet, movable toward and away from the cards, moves cards not locked out of alignment with locked cards, the combination of means for moving the said magnet associated with means for energizing and de-energizing the said magnet at timed intervals.

2. In a card record apparatus in which magnetically attractive cards having lugs formed in an edge thereof are selectively locked against movement by engaging the lugs on the cards with selectively settable selector members common to all of the cards and a card moving magnet, movable toward and away from the cards, moves cards not locked out of alignment with locked cards, the combination of means for moving the said magnet associated with means for energizing and de-energizing the said magnet, and two magnet coils in association with the said magnet, said last named means energizing both of the said coils to influence the unlocked cards to move toward the said magnet when the said magnet is moving toward the cards and de-energizing one of the said magnet coils and maintaining the other of the said magnet coils energized to influence the unlocked cards to move with the magnet when the said magnet is moving away from the locked cards.

3. In a card record apparatus in which magnetically attractive cards having lugs formed in an edge thereof are selectively locked against movement by engaging the lugs on the cards with selectively settable selector members common to all of the cards and a card aligning magnet common to all of the cards aligns the cards in lug registering relationship with the selector members and a card moving magnet, movable toward and away from the cards, moves cards not locked out of alignment with locked cards, the combination of means for moving the card moving magnet associated with means for energizing and de-energizing both of the said magnets, and two magnet coils in association with the card moving magnet, said last named means energizing both of the said magnet coils to influence the unlocked cards to move toward the card moving magnet when the card moving magnet is moving toward the cards and de-energizing one of the said magnet coils and maintaining the other of the said magnet coils energized to influence the unlocked cards to move with the card moving magnet when

the card moving magnet is moving away from the cards and alternately energizing and de-energizing the card aligning magnet and the first named magnet coil.

5. In a card record apparatus in which magnetically attractive cards having lugs formed in an edge thereof are selectively locked against movement by engaging the lugs on the cards with selectively settable selector members common to all of the cards and a card aligning magnet common to all of the cards aligns the cards in lug registering relationship with the selector members and a card moving magnet, movable toward and away from the cards, moves cards not locked out of alignment with locked cards, the combination of means for moving the card moving magnet associated with means for energizing and de-energizing both of the said magnets at timed intervals.

10. 5. In a card record apparatus in which selectively operable cards having lugs formed in an edge thereof are selectively locked against movement by engaging the lugs on the cards with selectively settable selector members common to all of the cards and a force, movable in relation to the cards and common to all of the cards, moves cards not locked out of alignment with locked cards and said force is other than the force of gravity, the combination of means for movably positioning the said force relative to the cards, associated with means for varying the magnitude of the said force.

15. 6. In a card record apparatus in which selectively operable cards having lugs formed in an edge thereof are selectively locked against movement by engaging the lugs on the cards with selectively settable selector members common to all of the cards and a force, movable in relation to the cards and common to all of the cards, moves cards not locked out of alignment with locked cards and said force is other than the force of gravity, the combination of means for movably positioning the said force relative to the cards, associated with means for varying the magnitude of the said force, said last named means applying the said force to move the unlocked cards to a position away from the locked cards and applying a portion of the said force to further move the unlocked cards to a position different from the first named position.

20. 7. In a card record apparatus in which selectively operable cards having lugs formed in an edge thereof are selectively locked against movement by engaging the lugs on the cards with selectively settable selector members common to all of the cards and a force common to all of the cards aligns the cards in lug registering relationship with the selector members and a force, movable in relation to the cards and common to all of the cards, moves cards not locked out of alignment with locked cards and said forces are other than the force of gravity, the combination of means for movably positioning the last named force relative to the cards, associated with means for varying the magnitude of the said last named force and alternately applying both of the said forces to the cards.

25. 8. In a card record apparatus in which selectively operable cards having lugs formed in an edge thereof are selectively locked against movement by engaging the lugs on the cards with selectively settable selector members common to all of the cards, the combination of means releasably holding and means for locking the selector

members against being moved into card locking relationship.

9. In a card record apparatus in which selectively operable cards having lugs formed in an edge thereof are selectively locked against movement by engaging the lugs on the cards with selectively settable selector members common to all of the cards and a force common to all of the cards aligns the cards in lug registering relationship with the selector members and the said force is other than the force of gravity, the combination of means releasably holding and means for locking the selector members against being moved into card locking relationship, and means for operating the said means and applying the first named force to the cards.

10. In a card record apparatus in which selectively operable cards having lugs formed in an edge thereof are selectively locked against movement by engaging the lugs on the cards with selectively settable selector members common to all of the cards and a common member which contacts all of the selector members and moves with selector members when selector members move into card locking relationship, the combination of means releasably holding and means for locking the said common member against movement.

11. In a card record apparatus in which selectively operable cards having lugs formed in an edge thereof are selectively locked against movement by engaging the lugs on the cards with selectively settable selector members common to all of the cards and a force common to all of the cards aligns the cards in lug registering relationship with the selector members and the said force is other than the force of gravity and a common member which contacts all of the selector members and moves with selector members when selector members move into card locking relationship, the combination of means releasably holding and means for locking the said common member against movement, and means for operating the first named means and applying the said force to the cards.

12. In a card record apparatus in which magnetically attractive cards having lugs formed in an edge thereof are selectively locked against movement by engaging the lugs on the cards with selectively settable selector members common to all of the cards and a card aligning magnet common to all of the cards aligns the cards in lug registering relationship with the selector members, the combination of means releasably holding and means for locking the selector members against being moved into card locking relationship an electromotive device for actuating said means; an electric circuit embracing the said electromotive device and the card aligning magnet; and a manually actuated switch arranged in the said electric circuit for operating the said electromotive device and the card aligning magnet.

13. In a card record apparatus in which magnetically attractive cards having lugs formed in an edge thereof are selectively locked against movement by engaging the lugs on the cards with selectively settable selector members common to all of the cards and a card aligning magnet common to all of the cards aligns the cards in lug registering relationship with the selector members, the combination of means releasably holding and means for locking the selector members against being moved into card locking relationship, and means operating the first named means

and energizing and de-energizing the card aligning magnet.

14. In a card record apparatus in which magnetically attractive cards having lugs formed in an edge thereof are selectively locked against movement by engaging the lugs on the cards with selectively settable selector members common to all of the cards and a card aligning magnet common to all of the cards aligns the cards in lug registering relationship with the selector members and a common member which contacts all of the selector members and moves with selector members when selector members move into card locking relationship, the combination of means releasably holding and means for locking the said common member against movement, and means operating the first named means and energizing and de-energizing the card aligning magnet.

15. In a card record apparatus in which magnetically attractive cards having lugs formed in an edge thereof are selectively locked against movement by engaging the lugs on the cards with selectively settable selector members common to all of the cards and a card aligning magnet common to all of the cards aligns the cards in lug registering relationship with the selector members, the combination of an armature member which contacts all of the selector members, means releasably holding and means for locking the said armature member against movement, and means for operating the first named means and energizing and de-energizing the card aligning magnet.

16. In a card record apparatus in which selectively operable cards having lugs formed in an edge thereof are selectively locked against movement by engaging the lugs on the cards with selectively settable selector members common to all of the cards, the combination of means releasably holding and means for locking the selector members against being moved into card locking relationship and an electromotive device for actuating the said first mentioned means.

17. In a card record apparatus in which selectively operable cards having lugs formed in an edge thereof are selectively locked against movement by engaging the lugs on the cards with selectively settable selector members common to all of the cards, the combination of means releasably holding and means for locking the selector members against being moved into card locking relationship, an electromotive device for actuating the said first mentioned means, an electric circuit embracing the said electromotive device and a manually actuated switch for the said electromotive device arranged in the said electric circuit.

18. In a card record apparatus in which magnetically attractive cards having lugs formed in an edge thereof are selectively locked against movement by engaging the lugs on the cards with selectively settable selector members common to all of the cards and a card aligning magnet common to all of the cards aligns the cards in lug registering relationship with the selector members and a card moving magnet common to all of the cards moves cards not locked out of alignment with locked cards, the combination of an electric circuit embracing the said magnets, a manually actuated switch included in the said electric circuit for energizing the said electric circuit, and a manually actuated switch included in the said electric circuit for de-energizing the card aligning magnet while permitting the energizing of the card moving magnet.

19. In a card record apparatus, the combination with means for moving a card moving magnet associated with means for energizing and de-energizing the said magnet and a card aligning magnet of two magnet coils associated with the said card moving magnet, means energizing and deenergizing both of the said two magnet coils, and means alternately energizing and de-energizing one of the said two magnet coils and the said card aligning magnet.

JOHN W. WHITSON.
